UNITED STATES PATENT OFFICE.

WILLIAM H. HOLLAR, JR., OF PHILADELPHIA, PENNSYLVANIA.

SAFE OR VAULT DOOR.

1,369,660.

Specification of Letters Patent. Patented Feb. 22, 1921.

Application filed June 20, 1919. Serial No. 305,548.

To all whom it may concern:

Be it known that I, WILLIAM H. HOLLAR, Jr., a citizen of the United States, residing at Philadelphia, in the county of Philadelphia and State of Pennsylvania, have invented certain new and useful Improvements in Safe or Vault Doors, of which the following is a specification.

My invention relates to improvements in safe or vault doors wherein the boltwork of the locking devices is carried by a plate of comparatively soft or machinable metal secured to the main body portion of the door which is formed of relatively hard or non-machinable metal, such as manganese steel.

The object of my invention is to improve the means to secure the boltwork plate to the body portion of the door and to provide a securing means which shall not only be simple, inexpensive, and efficient, but shall be inclosed and confined within the main body of the door.

With the above and related objects in view, the invention consists in the novel construction and combinations of parts hereinafter fully described and claimed.

In the accompanying drawings illustrating my invention,

Figure 1 is a view of a safe door embodying my invention, as seen from the interior of the safe and partly broken away and partly in section.

Fig. 2 is a section through the door, on line 2—2 of Fig. 1.

Fig. 3 is a view of the sectional locking member.

Referring to the drawings, 3 designates the main body portion of a door which is formed of extremely hard and tough metal, preferably a casting of manganese steel. The body portion 3 comprises a front wall 4 having an annular rim 5 projecting rearwardly therefrom and an annular flange 6 projecting inwardly from the rim 5 in spaced relation to the front wall 4. The periphery of the rim 5 is suitably shaped to fit against the jamb or wall of a safe or vault when the door is closed against the same.

50 The rear or inner wall of the door comprises a plate 7 which is formed of relatively soft or machinable steel so that parts thereof may be properly machined or finished to re-

ceive parts of the boltwork of the locking devices for the door, which the plate is 55 adapted to carry. The plate 7 is provided with two inwardly-extending annular flanges 8 and 9 through which a circular series of radially extending locking bolts 10 extend. The bolts 10 are slidably fitted to the flanges 60 8 and 9 and they are adapted to be projected into and retracted from locking position by suitable mechanism not shown in the drawings. The boltwork or locking mechanism may be similar to that shown and described 65 in Letters Patent No. 621,341, dated March 21, 1899.

The main body of the plate 7 is fitted within the flange 6, and the plate 7 has an outwardly-extending annular flange or lip 70 11 which is seated against the flange 6 and rim 5, as shown. Suitable dowel pins 12 are provided which extend through the flange 11 and into the rim 5 and prevent circular displacement of the plate 7 relatively to the 75 main body 3 of the door.

Arranged between the plate 7 and the forward wall 4 of the body 3 is an annular sectional locking member 13, formed of a circular series of segmental plates 14 which 80 permit the entire locking member 13 to be contracted to be passed through the flange 6 to a position within the rim 5 and thereafter expanded to engage the flange 6 between it and the front wall 4, in assembling 85 the parts. When the locking member 13 is thus expanded, the sections 14 thereof are secured to the plate 7 by suitable screws 15 and 16 which extend through the plate 7 and are screwed into the sections 14, as 90 clearly shown in the drawings. When the parts are assembled, as just described, the flange 6, being clamped between the locking member 13 and the plate flange 11, prevents displacement of the plate 7 either 95 toward or from the front wall 4 of the door body 3, and the body 3 and plate 7 are thus firmly secured together.

The hollow body portion 3 is filled with concrete in which may be embedded suitable 100 burglar and fire proof elements such as the plate 17 of manganese steel, the plate 18 of non-burnable metal and the steel rods 19 shown in the drawings, the whole forming a solid door structure inclosing within the 105 body thereof the means which secures the

boltwork plate 7 to the manganese casting 3 which forms the frame or main body portion of the door.

I claim as my invention:—

- 5 1. In a safe door, a body portion having a front wall, a rim, and an inturned flange on the rim, a plate, and a locking member separable from and secured to the plate and extending between the front wall and the
- 10 10 flange and preventing movement of the plate from the body portion.
2. In a safe door, a body portion having a front wall, a rim, and an inturned flange on the rim, a plate, and a locking member separable from and secured to the plate, said flange extending between the plate and the locking member.
- 15 3. In a safe door, a body portion, a plate,

a sectional locking member comprising a circular series of independently movable sections, and means to secure the sections of the member to the plate, said member engaging a part of the body portion and preventing movement of the plate from the body portion.

20 4. In a safe door, a body portion having a front wall, a rim, and an inturned flange on the rim, a plate, a sectional locking member comprising a circular series of independently movable sections, and means to secure the sections of the member to the plate, said flange extending between the plate and the locking member.

25 In testimony whereof, I affix my signature hereto.

WILLIAM H. HOLLAR, JR.
